UNITED STATES PATENT OFFICE.

PERRY BROWN, OF CORAOPOLIS, PENNSYLVANIA.

BRAKE.

1,185,973

Specification of Letters Patent.

Patented June 6, 1916.

Application filed September 23, 1914 Serial No. 863,148.

To all whom it may concern:

Be it known that I, Perry Brown, a citizen of the United States of America, and a resident of Coraopolis, in the county of Allegheny and State of Pennsylvania, have invented certain new and useful improvements in Brakes, of which the following is a specification:

This invention relates to improvements in brakes of that character shown in my Patents Nos. 1,057,429 and 1,057,521, and in my application filed Sept. 27, 1913, Ser. No. 792,173.

The invention consists in improvements on the brakes shown in said patents and application and will now be described and hereinafter claimed at the end hereof.

In the drawings accompanying and forming part hereof and which show the preferable, but not the necessary embodiment of my invention, Figure 1 is a plan view of my brake with parts shown in section. Fig. 2 shows several of the parts in perspective view, detached from each other in order that their operation may be better seen. Fig. 3 is a vertical section. Fig. 4 is a perspective view with the two handles partly broken away. Figs. 5, 6 and 7 are views of a modified form.

Referring now to the details of the drawings by numbers: 1 and 2 designate two parts of a frame adapted to be riveted or otherwise secured to the end of a car, the upper part 1 having a head 4 and the lower part 2 a horizontally disposed flange 6 which is provided with a cup-shaped member 8 adapted to form part of a housing for the ratchet 10. As illustrated, the head 4 of the upper part 1 and the flange 6 of the lower member 2 are securely bolted together by means of the bolt 12. The brake rod or shaft 16 projects upwardly through the cup-shaped housing 8 and has a squared portion 18 which fits into a similarly shaped opening in the ratchet 10 so that the ratchet 10 and said bolt or shaft 16 must turn together. Immediately over the cup-shaped housing 8 and between it and the head 4 is the upper part 20 of the housing. This upper housing 20 and the head 4 are adapted to receive the cylindrical part 22 of the staff

or staff, so that the hood forms a bearing for the staff and so that the upper housing can then on the part 22 of the staff in a manner readily understood from the drawings. The upper part of the housing 20 is formed with an offset 24 which forms a socket to receive a handle or lever 26 and the latter is pivoted to the offset on the bolt 28 so as to drop by gravity to a vertical position as shown in dotted lines in Fig. 3 or so that it may be moved by the brakeman to the position shown in full lines in Figs. 1, 3, 4 and 7. This handle is provided with a sliding pawl 30 which is adapted to coact with the ratchet 10 and which is held in the handle by the pin 32. This pin, however, fits in a slot 34 in the sliding pawl so that the pawl may have movement on the pin 32 to the limit of the slot 34 or until the pawl 30 engages the ratchet 10. A spring 36 is located behind the sliding pawl 30 so as to normally hold said pawl in engagement with the ratchet 10 if the handle is held in its operative horizontal position. It sometimes becomes necessary to lock the sliding pawl 30 in its outer position so that it will act upon the ratchet 10 no matter whether the handle is turned to the right or to the left, and to accomplish this purpose, I form an opening 38 in the handle to the rear of the chamber containing the spring 36 and in this opening 38 is located a bolt 40, the free end of which 42 projects within the spring 36 and is long enough to act upon the sliding pawl 30. This bolt 40 is provided with a handle 44 which projects through a slot 46 in the lever 26 so that it may be moved by the brakeman whenever necessary, and the handle 44 when moved longitudinally of the lever 26 may also be moved laterally of the lever so as to fit within a recess 50 (shown in dotted lines in Fig. 1) whereby the handle 40 will be restrained from rearward movement and thereby hold the sliding pawl 30 in the position shown in said Fig. 1. When it is desired to permit the pawl to move to the rear and free the ratchet, the handle 40 is moved so as to be out of the recess 50 and then the pawl can slide against the tension of the spring 36.

In order to hold the ratchet 10 in the po-

sition to which it is moved by the operating lever 26, I employ a pivoted pawl 60, which is pivoted to the same bolt 42 which has been described as holding the parts of 5 the frame together. This pivoted pawl is provided with a spring 62 which normally holds the pawl in contact with the teeth of the ratchet 10, but which permits the pawl to swing outwardly to permit the 10 ratchet to be turned when necessary. This pivoted pawl is provided with a handle 64 but instead of being integral as shown in my prior devices, the handle is separate 15 from the pawl but nevertheless is arranged so that it can move the pawl in one direction when such movement is necessary, the pawl being provided with an extension 61 against which the end of the handle 64 abuts to cause simultaneous movement when desired. 20 It will thus be seen that the pivoted pawl is so arranged that when the operator moves the operating lever 26 to apply the brake, the ratchet 10 is rotated and, in rotating, forces the pivoted pawl 60 outward against 25 the tension of its spring 62 without moving the handle 64, but that when it is necessary for the operator to move the pivoted pawl 60 to release the ratchet and thereby release the brake, it is only necessary to move 30 the handle 64 which will thus be caused to move against the pawl 60 and move it out of contact with the ratchet 10. The handle 64 is pivoted to the same bolt 42 on which the pawl 60 is pivoted, so that this bolt 35 serves the purpose of a pivot for both the pawl and the handle and also serves to secure together the parts of the frame.

From an inspection of Fig. 2, it will be observed that the handle 64 is provided with 40 a projecting flange 72 which is shaped and designed to cooperate with the walls 74 of the housing and thus close the opening through which the handle 64 and pawl 60 project.

45 In Figs. 5, 6 and 7, I have shown a modification in which, instead of using a horizontally operating handle 64 as in the other figures, I employ a vertically operating handle 80. This handle 80 has trunnions 82 which work in a bearing formed in a casing 84 cast upon the upper part of the frame 1. The handle 80 is also formed with a lug 86 shown in dotted lines in Fig. 6 as projecting on one side of the handle and this 55 lug is designed, when the handle is moved to work against a lug 88 on the pawl 90 and move it against the tension of its spring.

The operation of my brake has been sufficiently indicated in the description of the 60 parts of the brake and therefore no separate description of the operation is necessary.

It will be obvious that changes and modifications may be made in the form and construction of the parts without departing

from the spirit of my invention, the scope 65 of which is indicated by the appended claims.

What I claim as my invention is:

1. In a brake, the combination of a staff, a ratchet, a pawl adapted to co-act with and hold said ratchet, a spring for normally holding said pawl against said ratchet but permitting it to move away from the ratchet as the ratchet is turned, and a lever constructed and arranged to move said pawl 75 away from said ratchet in opposition to said spring, said pawl having movement in one direction independent of said handle, substantially as described.

2. In a brake, the combination of a staff, 80 a housing, a ratchet in said housing moving with said staff, a pawl, a spring normally holding said pawl in engagement with said ratchet but permitting the pawl to yield as the ratchet moves in one direction, and a handle extending outside of the housing and having a member co-acting with said pawl to move the same away from said ratchet against the tension of the aforesaid spring, said pawl having movement in one 90 direction independent of said handle, substantially as described.

3. The combination of a staff, two members co-acting therewith and forming a housing, a bolt for securing said members 95 and the housing together, a ratchet located in said housing and rotatable with said shaft, a pawl pivoted on said bolt and adapted to co-act with and hold said ratchet, a spring normally holding the pawl against 100 said ratchet but permitting it to move away from the ratchet as the ratchet is turned, and a handle also pivoted on said bolt for operating said pawl, in opposition to said spring, said pawl having movement independent of 105 said handle substantially as described.

4. In a brake, the combination of a shaft, a housing, a lever or handle projecting through said housing, a ratchet in said housing, and a flange on said lever or handle 110 covering the opening through which the lever projects, substantially as described.

5. The combination of a staff, a ratchet, and a handle for moving said ratchet, said handle having a sliding pawl, a spring for 115 operating said pawl, and a bolt for holding said pawl in its active position, substantially as described.

6. The combination of a staff, a ratchet, and a handle for said ratchet, a spring actuated pawl sliding in said handle, and a sliding bolt located behind said pawl and adapted to be moved to lock said pawl in engagement with said ratchet, substantially as described.

7. The combination of a staff, a ratchet, and a handle for said ratchet, a spring actuated pawl sliding in said handle, the spring

normally holding said pawl in its outer position but permitting it to be moved inward, a bolt located behind said pawl and slideable against the pawl to hold the pawl in its 5. outer position, said bolt having a handle to lock the same in position, substantially as described.

In testimony whereof I affix my signature in presence of two witnesses.

PERRY BROWN.
